DEVICE FOR MARKING X-RAY NEGATIVES

Edward S. Auer, Chicago, Ill.

Application April 10, 1936, Serial No. 73,634

6 Claims. (Cl. 250—34)

This invention relates to certain novel and useful improvements in a device for marking X-ray negatives, and has for its principal object the provision of an improved construction of this character which will be highly efficient in use and economical in manufacture.

Among the several objects of this invention is the provision of a device of the character hereinafter more fully described and claimed wherein means is provided to facilitate the interchangeability of identification indicia with a frame or holder.

A further object of my invention is the provision of a frame or holder of a substance or material which is transparent to the X-rays, and which is so designed and constructed to receive an indicia bearing identification plate or plates an indicia bearing identification plate or plates freely slideable with respect thereto and formed of a material which is not transparent to the X-rays so that after the operation of photographing has taken place, the identification indicia and characters will clearly appear upon the negative free from any apparent association with a frame or the like.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a front elevational view of the device embodying the invention for marking X-ray negatives;

Fig. 2 is an enlarged sectional detail view of the same taken substantially on line 2—2 of Fig. 1; and

Fig. 3 is a fragmentary enlarged perspective view of the device embodying the invention.

In accomplishing the several objects of the invention, some of which are herein recited, I prefer to provide a frame or holder 10 of a substance such as aluminum or sheet metal which is transparent to the X-rays of an X-ray apparatus.

This holder 10 includes a back 11 and oppositely spaced longitudinally extending side walls or flanges 12 spaced from the back wall 11 to provide opposing parallel grooves 13 having unobstructed end portions to facilitate the insertion therein of the edge portions 14 of an identification plate 15 which is freely slideable in these grooves 13 for insertion within the frame 10 from a direction from either of the open unobstructed end portions 13.

The side walls or flanges 12 are substantially

spaced from each other for reasons which will appear apparent from the description to follow.

In the preferred form of construction, the plate 15 provides parallel intermediate bars 16 spaced from each other to provide a medial opening 17, and these bars 16 are spaced from the side bars 18 of the plate identification or frame 15 to provide side openings or spaces 20. This frame is formed of a substance such, for example, as lead, which is opaque to the X-rays, so that the same will register upon the negative.

The identification letters or characters are indicated at 19 and are formed of a substance, such as lead, which is relatively impervious to the X-rays, and in the preferred form of construction 15 these letters or characters are adhesively secured to a flexible background 21 in the form of an adhesive tape adhesively secured to the plate 15 in a manner such that the identification letters or characters will be disposed within the spaces 20.

Mounted forwardly of the plate with its opposite edge portions confined in the grooves 13 is a plurality of transparent sheets 22 of glass or a non-rigid substance like cellulose acetate or celluloid, and these sheets 22 in the preferred form of construction are adapted to have adhesively secured thereto identification numerals or characters 23 to identify, such as, for example, the date when the X-ray was taken, the number 30 thereof, and such other information as is necessary to properly mark the X-ray negative for identification.

The sheets 22 preferably have these numerals or characters 23 adhesively or otherwise secured 35 thereto in such a manner as to position them within the confines of the space 17, and these numerals and characters like the plate 15 and the letters or characters 18 are of a substance, for example lead which is relatively opaque to the 40 X-rays.

From the description herein taken in connection with the accompanying drawing, it is manifest that the several parts being freely slideable within the frame 15 may be expeditiously removed so that other identification characters and numerals may be associated with this frame.

Again, by mounting the identification numerals or characters upon sheets separate from the plate 15 where a number of X-rays are taken 50 of one subject, it is only necessary to remove the identification numbers or characters and substitute other identification numbers and characters therefor without removal of the plate 15 from the frame 10.

- While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.
- Having thus described my invention, what I claim as new and desire to protect by Letters Patent is:
1. A device for marking X-ray negatives consisting of a frame having oppositely disposed grooves and formed of a substance transparent to X-rays, an identification plate having its longitudinal edge portions freely slideable in the grooves and of a substance opaque to the X-rays, supplemental sheet elements having their opposite longitudinal edge portions freely slideable in the grooves in front of the said plate, and identification indicia mounted on said sheet elements and of a substance opaque to the X-rays.
  2. A device for marking X-ray negatives consisting of a frame having oppositely disposed grooves and formed of a substance transparent to X-rays, an identification plate having its longitudinal edge portions freely slideable in the grooves and of a substance opaque to the X-rays, supplemental sheet elements having their opposite longitudinal edge portions freely slideable in the grooves in front of the said plate, identification indicia mounted on said sheet elements and of a substance opaque to the X-rays, said plate being provided with a longitudinal opening, identification characters mounted in said opening and of a substance opaque to the X-rays, and means for supporting said identification characters in said opening comprising a member adhesively secured to said plate and of a substance transparent to the X-rays.
  3. A device for marking X-ray negatives consisting of a main frame member of X-ray-pervious-material and having a pair of oppositely disposed grooves, an identification plate opaque to X-rays and having a plurality of cut-away portions with indicia members supported within some of said cut-away portions by means of an X-ray pervious backing strip attached to said plate and having said indicia members attached thereto, the said plate being slideable into and out of said grooves in said frame, and a second plate of X-ray-pervious-material slidably supported in said grooves of said frame on top of the said identification plate and having indicia members attached thereto, said members being opaque to X-rays, and being positioned on said second plate so as to overlie other cut-away por-

tions of said identification plate not occupied by said first-mentioned indicia members.

4. A device for marking X-ray negatives consisting of a first main frame having a pair of open ended grooves on opposite edge parts thereof, a second frame slideable into the grooves of said first frame and having an elongated central opening, and a transparent plate member slideable into the grooves of said first frame over said second frame and having attached thereto indicia characters formed of an X-ray-impervious substance and positioned thereon to overlie said central opening in said second frame when the several said members are in assembled relation as aforesaid.

5. A device for marking X-ray negatives comprising a main frame in the form of a substantially elongated plate of X-ray-pervious-material and having a pair of opposite edge portions upturned to form open-ended grooves, an identification frame of substantially elongated shape formed of a substance opaque to X-rays and having an elongated central opening flanked by a pair of outer openings and X-ray-impervious indicia members supported in the last-mentioned flanking openings upon an X-ray-pervious backing strip secured to said frame, said identification frame being slideable in the grooves of said main frame, and an indicia plate of X-ray-pervious material slideable in the grooves of said main frame over said identification frame and having X-ray-impervious indicia characters secured thereto in a position to overlie the said central elongated opening of the identification frame when the latter and said indicia plate are in assembled relation in said main frame.

6. A device for marking X-ray negatives comprising a main frame member of X-ray-pervious-material having a pair of open-ended oppositely disposed edgewise grooves, an identification frame formed of X-ray-impervious material and dimensioned to slide between the grooves of said main frame for positioning thereon, said identification frame having a plurality of openings therethrough with X-ray-impervious indicia characters supported in a first one of said openings by means attached to said frame and to said characters, and an indicia plate of X-ray-pervious material also slideable between said grooves of the main frame on top of said identification frame when the latter is positioned in the main frame, said plate having secured thereto X-ray-impervious indicia characters positioned thereon to overlie a second said opening in said identification frame and not occupied by identification indicia characters.

EDWARD S. AUER.
